UNITED STATES PATENT OFFICE.

ROBERT IRVINE, JR., OF WEST HARTLEPOOL, ENGLAND.

UMBRELLA-TENT.

SPECIFICATION forming part of Letters Patent No. 574,091, dated December 29, 1896.

Application filed November 18, 1895. Serial No. 569,349. (No model.) Patented in England April 26, 1895, No. 8,312.

To all whom it may concern:

Be it known that I, ROBERT IRVINE, Jr., a subject of the Queen of Great Britain, residing at West Hartlepool, England, have invented new and useful Improvements in Umbrella-Tents and in Holders for Tent and other Umbrellas, (for part of which I have obtained a patent in Great Britain, No. 8,312, dated April 26, 1895,) of which the following is a specification.

My invention chiefly relates to tents of the kind in which an umbrella is employed adapted to have the sides of the tent suspended therefrom; but my invention also comprises a holder by means of which the umbrella may be held at any desirable angle, the said holder being also applicable for holding other umbrellas, such as carriage-umbrellas.

The principal object of my invention is to provide means whereby an umbrella-tent may be erected without the necessity for making holes in the turf or surface upon which it is placed, and to provide means whereby suitable ventilation may be obtained.

According to my invention the umbrella is held in a holder or socket suspended by means of a universal joint in a suitable framing and adapted to be locked in any desired position, according to the angle or position in which it is desired to hold the umbrella.

The sides of the tent may be suspended from the ribs of the umbrella in the usual manner, and in order to retain the lower edges of the sides in proper position without the use of tent-pegs, I provide what I term a "weight-ring," which is jointed or made in sections, so that it may be packed into comparatively small space, and to which the lower edges of the sides may be hooked or connected.

To provide for the ventilation of the tent, I arrange for lifting the umbrella relatively with the sides and the sides relatively with the weight-ring, so that spaces may be left between the sides and the umbrella or between the sides and the ground, or both.

To enable my invention to be fully understood, I will describe the same by reference to the accompanying drawings, in which—

Figure 1 is a perspective view of the tent having my improvements applied thereto, and Fig. 2 is a perspective view of the umbrella with its holder. Fig. 3 is a plan of the

holder with the umbrella removed and drawn to an enlarged scale, and Fig. 4 is an elevation of the said holder. Fig. 5 is a sectional view, drawn to an enlarged scale, of the universal joint of the holder, showing a clamp for fixing the same; and Fig. 6 is a plan view, also drawn to an enlarged scale, of a clamp arranged upon the base-plate and serving to receive the lower end of the holder or socket when in a vertical position. Fig. 7 is a sectional view showing the means I employ for adjusting the height of the umbrella in the holder. Fig. 8 is a sectional view showing a table applied to the holder, and Fig. 9 is an under-side view of the said table. Fig. 10 is a sectional view showing the arrangement for suspending the sides when the umbrella is lifted for forming a space between the umbrella and the top edge of the said sides. Fig. 11 is a similar view illustrating a modification of this arrangement. Fig. 12 is a sectional view of part of the weight-ring shown in Fig. 1. Fig. 13 is a view similar to Fig. 12 of a modified arrangement of weight-ring; and Fig. 14 is a section of the said ring on the line 14 14, Fig. 13. Fig. 15 is a view of a portion of the lower edge of the curtain, showing one of the hooks for attachment to the weight-ring.

Similar letters of reference indicate corresponding parts in the several figures.

a is a base-plate of the holder, and *b b* are arms or brackets projecting upward from the said plate.

c is the holder proper, in which the stick or shaft *d* of the umbrella is placed. As hereinbefore stated, this holder *c* is carried in the framing by means of a universal joint. As shown in the drawings, this joint is a ball-and-socket joint, the socket being formed at the upper ends of the arms *b b* and the ball being formed upon the holder *c*, as clearly shown in Fig. 5.

In order to lock the holder in any position in which it may be placed, for instance, in the position shown in Fig. 2, I provide a set-screw *e*, adapted to act upon a movable pressure piece or pad *e'* and to press the same against the ball, as shown clearly in Fig. 5.

To insure that when desired the holder may be fixed in a vertical position, I form at the center of the base-plate *a* a nipple or collar *f*,

(shown most clearly in Fig. 6,) the said nipple having an opening in one side to allow the end of the holder to pass into it, as shown in Fig. 4, a pin f' being then inserted to lock the holder in the vertical position.

In manufacturing my holder the arrangement of the arms b should be such that when the holder proper is inclined it shall under no circumstances come into contact with the 10 arms b or so near thereto as to nip the fingers of the person manipulating the said holder.

g g are holes formed through the holder c , and h is a pin designed to be inserted through one or the other of the said holes, as shown in 15 Fig. 7, in order to regulate the height of the umbrella in the holder.

i is a table which I advantageously make use of in connection with my holder. The said table is provided with a central opening 20 to allow the free movement of the holder c within it and is carried on the casing of the universal joint. As shown, the said table is represented as provided with two claws i' at its under side, the said claws being adapted 25 to pass through notches i^2 i^2 , Fig. 3, formed in the edges of the said casing, and when the table is slightly turned to engage beneath the flanges i^3 of the said casing, as shown in Fig. 8.

j is the umbrella, having the ribs k k , and l 30 is the piece of fabric forming the tent sides, the said piece of fabric having attached to it a series of hooks, such as m , Fig. 10, adapted to engage with rings, such as n , on the ribs of the umbrella to support the sides in the usual manner.

o is the weight-ring, which is of the same diameter as the umbrella when open, the said ring being made in sections jointed together, so that it may be packed into a relatively small 40 compass. This ring is of such weight that when it lies upon the ground and hooks (such as p) on the lower edge of the sides are connected thereto, as shown in Fig. 15, the said sides will be held in position in the same manner as if attached to tent-pegs, as heretofore.

The arrangement for providing top ventilation is as follows: Around the top of the said sides a cord q passes through eyes q' q' , a pair of such eyes being adjacent to each hook m , 50 as in Fig. 10, so that by slackening the cord sufficiently loops r may be formed of sufficient length that when passed over hooks s on the ends of the umbrella-ribs, Fig. 10, the desired space will be obtained between the top of the 55 sides l and the umbrella. Fig. 1 represents the umbrella raised above the sides to provide a space for top ventilation.

Instead of using the cord q I may attach to the sides l a series of straps q^2 and hooks q^3 , 60 the said straps being adapted to pass through the rings n , as shown in Fig. 11, and being provided with two or more eyelets q^4 , either of which may be engaged with the hooks q^3 , according to the space desired.

65 To provide for bottom ventilation in case such is required, I make the weight-ring o tubular, and I pass a cord o' through it, the

said cord, at points corresponding with the position of the various hooks p on the bottom of the sides, being passed through the sides 70 of the tube, as shown in Fig. 12, so as to permit of forming longer or shorter loops o^2 , according to the bottom space desired. It is to be understood that the said hooks p are engaged with the several loops o^2 on the weight-ring, the said loops being long enough to permit of the ring always lying upon the ground. 75

It will be obvious that when using either the top or bottom ventilation it will be necessary to raise the umbrella-stick d in the holder 80 sufficiently far to tighten the sides to the required extent.

Instead of making the weight-ring tubular it may be a plain bar provided with eyes t t , as shown in Figs. 13 and 14, through which 85 the cord is passed.

Having now particularly described and ascertained the nature of my said invention and in what manner the same is to be performed, I declare that what I claim is—

1. In an umbrella-tent holder the combination with the supporting-frame provided with a bearing-support, of a tubular socket adapted to receive the umbrella-stick, a spherical enlargement upon said socket adapted to engage the bearing-support, a clamping device connected with said bearing-support for adjusting the position of the said spherical enlargement and said tubular socket in respect to said bearing and an adjusting device on 90 said tubular socket, separate from said clamping device for adjusting the umbrella-stick longitudinally in said socket, substantially as described. 95

2. In an umbrella-tent holder, the combination with the supporting-frame provided with a bearing-support, of a tubular socket provided with a longitudinal series of apertures and a spherical enlargement for engaging said bearing-support, a clamping device for adjusting said spherical enlargement and said tubular socket with respect to the said bearing-support, and a pin for engaging one of said series of apertures in the tubular socket to adjust the umbrella-stick longitudinally in 115 said socket, substantially as described. 105

3. In an umbrella-tent holder, the combination with a tubular socket adapted to receive an umbrella-stick, a supporting-frame, adjustable devices on said frame for holding the 120 tubular socket in different angular positions and an auxiliary support for said tubular socket on said supporting-frame, in a different horizontal plane from said adjustable devices, substantially as described. 125

4. In an umbrella-tent holder, the combination with the tubular socket adapted to receive an umbrella-stick, of a supporting-frame provided adjacent to its upper part with adjustable devices for engaging said tubular 130 socket and holding it in different angular positions, said frame having an auxiliary support adjacent to its lower portion in a vertical line with said adjustable devices, adapted

to receive the lower end of said tubular socket to maintain it in vertical position and a retaining device for said auxiliary support, substantially as described.

5 5. In an umbrella-tent, the combination with an umbrella, of a central holder for the same, sides adapted to be hung from said umbrella, a separate weight-ring and devices for detachably securing the bottom edges of said sides to said ring, substantially as described.

10 6. In an umbrella-tent, the combination with an umbrella, of a central holder for the same, sides adapted to be hung from said umbrella, a separate weight-ring provided with 15 eyelets arranged at intervals, an adjustable flexible connection engaging said eyelets, and detachable retaining devices secured to the bottom edge of said sides, at intervals, and adapted to engage said flexible connection, 20 substantially as described.

25 7. In an umbrella-tent, the combination with an umbrella, of side portions adapted to be supported from said umbrella, a supporting-frame for engaging the umbrella-stick, a detachable weight-ring, an adjustable flexible connection for engaging said detachable weight-ring and said sides, for holding said sides at a greater or less distance from the ground, substantially as described.

30 8. In an umbrella-tent the combination

with an umbrella, of a holder for the same, side portions, flexible adjustable connections between the umbrella and the sides, a separate weight-ring and flexible, adjustable connections between the sides and the weight-ring, whereby the sides are adapted to be adjusted vertically to permit of ventilation at the top and bottom, substantially as described. 35

9. In an umbrella-tent, the combination with an umbrella, and a holder therefor, of 40 side portions and a jointed weight-ring, adapted to be folded in a compact form when not in use, substantially as described.

10. In an umbrella-tent, the combination of 45 a holder, an umbrella, side portions, a weight-ring and a flexible connection engaging the weight-ring at intervals and adapted to be engaged by parts connected with the side portions, substantially as described.

11. In an umbrella-tent, the combination of 50 an umbrella, a holder, side portions, a weight-ring, and a continuous flexible connection engaging eyes upon said ring and adapted to be engaged by parts connected with said portions, substantially as described.
